UNITED STATES PATENT OFFICE

2,446,494

SNOW FENCE MACHINE

Joseph D. Smith, Toronto, Ontario, Canada

Application March 8, 1945, Serial No. 581,673

6 Claims. (Cl. 140—30)

1

This invention relates to improvements in machines for making snow fences of the type in which wood slats are secured in parallel spaced relation by paired longitudinal wires which are twisted between the slats to grip and hold the slats securely and the principal object is to provide a machine which will operate with greater precision and speed in twisting the wires tightly around the slats as they are placed progressively between the paired lengths of wire.

The principal feature of the present invention consists in the novel construction and arrangement of mechanism whereby a plurality of rotatable wire holding forks adapted to span the slats as they are inserted into the machine are operated in unison to twist the wires tightly there-around by a quadrant gear member oscillated by a reciprocating member operatively connected to a single driving cam.

In the accompanying drawings

Figure 1 is a plan view of my improved machine. Figure 2 is a front end elevational view showing my improved wire twisting mechanism.

Figure 3 is an enlarged elevational detail of my improved cam mechanism for operating the reciprocating means for effecting the rotation of the wire twisting members.

Figure 4 is an end elevational view of the main operating cam showing the supports therefor in part vertical section through the line 4—4 of Figure 3.

Figure 5 is a vertical sectional view through the operating cam and its supports taken on the line 5—5 of Figure 3.

Figure 6 is an elevational view similar to Figure 3 showing the cam in the reverse position to that shown in Figure 3.

Figure 7 is a longitudinal sectional view of one of the wire twisting forks and a cross section of a portion of the fence fashioned thereby.

Figure 8 is an elevational part sectional detail of the means for braking the wire twisting members.

Figure 9 is a side elevational detail view showing the mechanism for feeding the slats into their final position close up to the twisted portion of the wires embracing the preceding slat.

In the construction herein shown the frame 1 of the machine is formed with a pair of parallel spaced transverse bars 2 and 3 carrying the aligned pairs of journal bearings 4 and 5.

Journalled in each aligned pair of said journals is a hollow shaft 6 upon the inner end of which is formed a fork 7, at the base of which

2

are arranged the eye holes 8, the tips of said forks having notches 9 therein.

A shaft 10 mounted in the frame 1 parallel with the bars 3 and 4 carries a plurality of grooved sheaves 11 over which pairs of wires 12 are fed from suitable reels (not shown).

The wires 12 are threaded through the hollow fork shafts 6 and leading out through the eye holes 8 the paired wires are carried over the 10 arched portions 13 of the forks and engage the notches 9 in the ends of the forks from whence such wires are formed around the slats 14.

Endless chain belts 15 are parallelly arranged and extend longitudinally at one side of the main 15 frame with the upper reach of each chain travelling over a flat table, which is omitted because it would hide part of the operating mechanism. The slats are placed on these chain belts, manually or otherwise and the belts feed the slats to 20 a position opposite the transversely aligned forks.

A frame 16 extending transversely of the machine and pivoted at the forward edge on hinges 17 carries a parallel pair of shafts 18 connected by a sprocket chain 19 and on the inward end of 25 each shaft is arranged a spur wheel 20. The slats 14 are fed beneath the spur wheels 20 by the belts 15 while the frame 16 is tilted upward and upon the lowering of the frame the rotating spur wheels engage the slats and project them through the fork members 7 and between the separated wires 12 while the forks are in a stationary position as shown in Figure 7.

The shafts 18 are driven by belts 21, 22 and 23 operated from the main drive shaft 24.

Each of the hollow fork shafts 6 has secured thereon, between the paired journals 4 and 5, a spur gear wheel 25 and these gears intermesh in a continuous train across the machine.

Upon the shaft of one of the forks is secured a 40 spur pinion 26 which meshes with an oscillatable quadrant 27 mounted on a shaft 28 and a lever 29 extends downwardly from the forward end of said shaft.

A lever 30, here shown formed of a pair of 45 spaced angle bars, is mounted on a pivot 31 intermediate of its length and its lower end is connected with the lever 29 by a bar 32.

A bar 33 pivotally connected at the top of the lever 30 extends in a horizontal direction across 50 the front end of the machine and is pivotally connected by an adjustable member 34 with a cross-head 35 which is slidably mounted in horizontal guides 36.

A shaft 37 journalled in one of the crossheads 55 guides and driven by a train of gears 38 connect-

ed with the main drive shaft 24 has mounted thereon between the crosshead guides a cam disc 39 formed with a face cam groove 40 in one side thereof. This cam groove is formed with a short concentric portion 41 which is connected by an eccentric portion 42 with a long concentric portion 43 and a second short eccentric portion 44 of said groove connects with the short concentric portion forming a somewhat heart-shaped groove.

Mounted on the spaced-apart cross bars 45 and 46 of the crosshead 35 are rollers 47 and 48 which engage the cam groove so that as the roller 47 operates in the short concentric groove 41, the roller 48 follows the long concentric groove 43 and while the roller 47 follows the long eccentric portion 42 the other roller 48 follows the short eccentric portion 44.

The thrust of the cam is thus distributed between the spaced-apart rollers of the crosshead which is operated first with a comparatively long movement in one direction followed by a stationary period while the rollers 47 and 48 travel in the concentric portions, then the crosshead is moved in the opposite direction.

This intermittent reciprocating movement of the crosshead operates the top bar 33, the end lever 30, the bottom bar 32, lever 29, shaft 28 and the quadrant 27 to rotate the pinion 26 and the train of fork gears, thereby turning the forks a definite predetermined number of turns to twist the wires 12 tightly around the slat which has been first placed transversely between the wires and then moved out of the forks.

The means for moving the slats out of the forks is particularly shown in Figure 9 in which a bar 49 extends transversely of the machine below the fork members 7 and has guide surfaces extending upwardly between the several forks to guide the slats centrally into said forks when propelled by the spur wheels 28.

Fingers 50 extend upwardly from the bar 49 between the fork members to engage the forward edge of the slat placed in the forks and the said bar is operated to push the slat edgeways out of the forks and into close engagement with the previously twisted wires 12.

Secured to each end of the bar 49 is a longitudinal bar 51 provided on the lower edge with rack teeth 52 which mesh with pinions 53 on a shaft 54 journalled transversely of the main frame.

A quadrant 55 mounted on the frame meshes with one of the pinions 53. A train of gears 56, 57, 58 driven from a shaft 59 operate a crank 60 on the shaft of the gear 58 and said lever has a crank pin 61 at its outer end connected to a link bar 62 which in turn is connected to the arm 63 of the quadrant.

The pinion shaft 54 has mounted thereon a crank 64 which operates a rod 65 connected with the hinged slat feed frame 16 to raise and lower the frame in synchronism with the operation of the bar 49 for moving the slats from the forks.

This slat controlling mechanism and the spacing and trimming mechanism is not a part of the present invention and is not described in complete detail herein.

An important feature in the present invention is to make provision for definitely locating the position of the wire twisting forks so that they will come to rest at the end of each operation of the cam-operated mechanism described with their sides in a vertical position so that the slats will enter same without obstruction. In order to accomplish this result and to enable accurate adjustment the hollow fork shaft 6 on which the

quadrant operated pinion 26 is mounted, is journalled in a bushing 65' rotatably mounted in the journals 4 and 5 and upon which bushings the driving fork gear 25 is mounted.

The rotatable bushing is formed with a clutch flange 66 and a mating clutch flange 67 is splined to the fork shaft 6. A lever 68 engaging the slideable clutch flange is operated by a toggle link connection 69 with a lever 70 pivotally mounted on the frame. The lever 70 is periodically operated by a cam 71 mounted on the shaft 59 or other shaft suitably connected so that at the desired instant the cam will engage the lever and operate the clutch to stop the rotation of the driving gear 25 and consequently all the rest of the train.

The lever 70 is provided with a suitable means for adjusting the contact with the cam 71 and is here illustrated as a leaf spring 72 adjusted by a set screw 73.

A machine as herein described is extremely accurate in its operation and the mechanism is rugged and will effectively withstand the strenuous operating motions and produces a uniformly secure fence in which the slats will be firmly held from displacement in the rugged service which it is called upon to give.

What I claim as my invention is:

1. In a machine for making snow fences, the combination with a frame, a plurality of rotatable parallel wire twisting members mounted on said frame and geared to rotate in unison, means for feeding paired wires to each of said twistlers, of a flanged bushing rotatably mounted on one of said wire twisting members, means for imparting rotative movement to said flanged bushing, a flanged member slidably and non-rotatably mounted on said wire twisting member adapted to engage the flange of the aforesaid bushing to drive the wire twisting member, and means for periodically operating said slideable clutch member to engage and disengage the flanged bushing.

2. In a machine for making snow fences, the combination with a frame, a plurality of rotatable parallel wire twisting members mounted on said frame and geared to rotate in unison, means for feeding paired wires to each of said twistlers, of a flanged bushing rotatably mounted relative to one of said wire twisting members, means for imparting rotative movement to said flanged bushing, a flanged bushing slidably and non-rotatably mounted on said wire twisting member and adapted to engage the flange of the aforesaid bushing to convey movement from said bushing to said wire twisting member, a lever operating to move said slideable member into and out of engagement with said flanged bushing, and cam-operated means for operating said clutch lever.

3. In a machine for making snow fences, the combination with a frame, a plurality of rotatable parallel wire twisting members mounted on said frame and geared to rotate in unison, means for feeding paired wires to each of said twistlers, of a flanged bushing rotatably mounted relative to one of said wire twisting members, means for imparting rotative movement to said flanged bushing, a flanged bushing slidably and non-rotatably mounted on said wire twisting member and adapted to engage the flange of the aforesaid bushing to convey movement from said bushing to said wire twisting member, a lever operating to move said slideable member into and out of engagement with said flanged bushing, toggle means for operating said lever, a lever connected with said toggle means, an adjustable contact

member mounted on said lever, and a cam arranged to engage said adjustable contact.

4. In a machine for making snow fences, the combination with a frame, a plurality of rotatable parallel wire twisting members mounted on said frame and geared to rotate in unison and means for feeding paired wires to each of said twisters, of an oscillatable member for operating said twisters to rotate first in one direction and then in reverse, a horizontal bar connected with said oscillatable member, a lever connected with said bar, a rod connected with the top of said lever, a crosshead mounted to slide horizontally and connected with said rod and having paired rollers, and a disc cam having a groove engaging said crosshead rollers and operating same with a reciprocation motion.

5. In a machine for making snow fences, the combination with a frame, a plurality of rotatable parallel wire twisting members mounted on said frame and geared to rotate in unison and means for feeding paired wires to each of said twisters, of an oscillatable member for operating said twisters to rotate first in one direction and then in reverse, a horizontally slidable crosshead operatively connected with said oscillatable member and having spaced-apart rollers extending from one side thereof, a cam disc having a cam groove formed with concentric curves connected by eccentric curves engaging said paired rollers and imparting on rotation reciprocating

movement to said crosshead and consequent reversing rotation to said wire twisters.

6. In a machine for making snow fences, the combination with a frame, a plurality of rotatable parallel wire twisting members mounted on said frame and geared to rotate in unison and means for feeding paired wires to each of said twisters of an oscillatable member for operating said twisters to rotate first in one direction and then in reverse, a horizontally slidable crosshead operatively connected with said oscillatable member and having spaced-apart rollers extending from one side thereof, a cam disc rotatably mounted adjacent said crosshead having a groove to engage said rollers formed with a short concentric portion and long and short eccentric portions connecting said concentric portions and imparting reciprocating movement to said crosshead.
